UNITED STATES PATENT OFFICE.

C. PERRIN SIMPSON, OF NEW YORK, N. Y.

URINAL.

SPECIFICATION forming part of Letters Patent No. 268,555, dated December 5, 1882.

Application filed September 7, 1882. (No model.)

To all whom it may concern:

Be it known that I, C. PERRIN SIMPSON, residing at New York city, in the State of New York, have invented a new and useful Improvement in Urinals, (an apparatus or machine to assist urination or make urination more convenient for invalids,) of which the following is a specification.

My invention relates to an apparatus or machine wherein the penis is laid, and the discharged urine is carried off without inconvenience to the user, or without requiring the user to be raised from the bed or couch.

The mechanism is illustrated by the accompanying drawing, in which the black mouth-piece A is the receptacle into which the penis may be laid or placed. The tubing B, through which the discharged urine is carried away, is

annexed to the black mouth-piece. It may be made of rubber or any other suitable material, and be of any desired length, and connects or passes through the center of a circular cover, C, also made of rubber, and which may be fastened or spread on and around the outer rim or edge of a vessel placed on the floor at the side of the bed or couch, and as the final receptacle of the urine.

What I claim, and desire to secure by Letters Patent, is—

The mouth-piece, tubing, and cover, substantially as described, combined together for the purposes herein set forth.

C. PERRIN SIMPSON.
